UNITED STATES PATENT OFFICE.

FRANK E. BLAISDELL, OF BOSTON, MASSACHUSETTS.

BILL-STRAP.

SPECIFICATION forming part of Letters Patent No. 451,657, dated May 5, 1891.

Application filed February 24, 1891. Serial No. 382,488. (No model.)

To all whom it may concern:

Be it known that I, FRANK E. BLAISDELL, of Boston, in the county of Suffolk, State of Massachusetts, have invented certain new and useful Improvements in Bill-Straps, of which the following is a description sufficiently full, clear, and exact to enable any person skilled in the art or science to which said invention appertains to make and use the same, reference being had to the accompanying drawings, forming part of this specification, in which—

Figure 1 is a perspective view showing my improved bill-strap in use; Fig. 2, a plan view of the strap opened; Fig. 3, a vertical longitudinal section of the strap partly open; Fig. 4, a like view showing the strap closed, and Figs. 5 and 6 plan views illustrating details of construction.

Like letters of reference indicate corresponding parts in the different figures of the drawings.

My invention relates especially to a strap for securing bank-notes together in bundles to prevent single notes from being abstracted; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation:

In the drawings, A represents the strap considered as a whole. Said strap consists preferably of a straight paper band, creased at d to readily fold over the edges of the notes. On the central portion or body f of the strap a re-enforcing strip g is secured, through which a vertically-arranged pin or brad h projects. One end i of the strap is enlarged and slotted at j to receive the opposite end k. The end k is gummed on the under side at m, and on the opposite face a series of columns p is imprinted, said columns being designated, respectively, "D," "M," and "Amt." designed for the insertion of the bills of a certain denomination in the first column, the number of such bills in the second column, and the total amount in the third column contained in the package, the gross

amount being footed up at the bottom. As illustrated in Fig. 5, the package would contain five one-dollar bills, ten two-dollar bills, &c., the gross amount thereof equalling one hundred dollars.

In use, the strap being opened, as in Fig. 3, the bills C are arranged in a pile, as shown in Fig. 1, and the pin h forced therethrough. The end i of the strap is then forced onto said pin, the point of which is turned over onto said end, as at r in Fig. 4. The end k of the strap is then passed through the loop j on the opposite end i, and secured thereto by moistening its gummed surface M. It is thus rendered practically impossible to abstract a single bill C from the strap without tearing it or breaking said strap. The amount in the bundle and the number of bills of any determined denomination being indicated in the columns p, verification is easily accomplished.

Having thus explained my invention, what I claim is—

1. A bank-note binder comprising a flexible strap having a brad or projection for penetrating the bills, and means for securing the ends of the strap together.

2. A bank-note binder or bill-strap comprising a body of flexible material provided with a centrally-disposed brad or pin for penetrating the bills, one end of said strap being gummed to attach it to the opposite end, substantially as set forth.

3. A flexible bill-strap provided centrally with a penetrating brad, one end of said strap being provided with a loop to receive the opposite end, said opposite end being gummed to secure it to the loop end, and provided on its outer face with spaces or columns in which the character of the contents of the bundle may be indicated.

4. The bill-strap A, having the gummed end k and loop end i, in combination with the pin h, secured centrally and vertically on said strap, substantially as set forth.

5. The strap A, provided with the loop j and gummed portion M, and the columns or spaces p, in combination with the pin h, secured vertically on said strap, substantially as set forth.

FRANK E. BLAISDELL.
